UNITED STATES PATENT OFFICE.

FRANK MAJKOWSKI, OF CHICAGO, ILLINOIS, ASSIGNOR OF ONE-HALF TO WALTER PIJAKOWSKI, OF CHICAGO, ILLINOIS.

RAILROAD-TIE AND RAIL-FASTENING MEANS.

1,319,405.

Specification of Letters Patent. Patented Oct. 21, 1919.

Application filed May 15, 1919. Serial No. 297,279.

To all whom it may concern:

Be it known that I, FRANK MAJKOWSKI, a citizen of Warsaw, in the territory formerly known as Russian Poland, now residing at Chicago, in the county of Cook and State of Illinois, and having heretofore formally declared my intention of becoming a citizen of the United States, have invented certain new and useful Improvements in 10 Railroad-Ties and Rail-Fastening Means, of which the following is a specification, reference being had to the accompanying drawings, forming a part thereof.

This invention relates to a metallic railroad tie having combined with it means for securing the track rails in place, all the parts being designed for economical production and with a view to giving extremely long service, thus avoiding the frequent replacement which makes the use of wooden ties relatively expensive. The invention consists in the features and elements of construction hereinafter described and shown in the drawings as indicated by the claims.

25 In the drawings:

Figure 1 is an elevation of a tie embodying this invention, being taken as a transverse section through the track rails shown supported by the tie.

30 Fig. 2 is a top plan view of the tie shown in Fig. 1, such parts being broken away to show in section various details of construction.

Fig. 3 is a detail section taken as indicated at line 3—3 on Fig. 2.

Fig. 4 is a detail section taken as indicated at line 4—4 on Fig. 2.

Fig. 5 is a detail section taken as indicated at line 5—5 on Fig. 4.

40 Fig. 6 is a detail section similar to Fig. 4, but showing a slightly modified construction.

The tie embodying this invention is designed to be made as a malleable casting of 45 the lightest possible cross section consistent with the necessary strength in order to insure economy in production and, as shown in the drawings, it consists of a horizontal web, 1, with marginal flanges, 2, extending 50 upwardly and downwardly therefrom in vertical planes perpendicular to the direction of the track composed of the rails, A. Additional stiffening ribs, 3, 3, may be added extending upwardly from the web, 1, 55 parallel to the flanges, 2, and spaced be-

tween them; and the area below said web, 1, is preferably inclosed by the depending portions of the flanges, 2, and end flanges, 4, 4, and the recess formed is filled with a cement mixture indicated at 5; for adding weight 60 and stability to the tie, and to some extent protecting its under surface from rust. If desired, additional ribs, 6, may be formed on the under surface of the web, 1, and the body of concrete, 5, may be bonded to the 65 metallic tie body by suspending a strip, 7, of woven wire or expanded metal lath in the space to be filled with concrete by means of pins, or rivets, 7^a, projecting from bosses, 6^a, formed in said ribs, the pins being secured therein by setting them in the mold at the time of casting the tie.

To provide seats for lodgment of the track rails, A, the side flanges, 2, are made thicker as indicated at 8, near each end of the tie, 75 and these thickened portions of the flanges are connected by heavy ribs running longitudinally of the direction of the track and positioned to extend just under each of the track rails, A. The tie illustrated in the 80 drawing is shown as having a continuous portion of rail lodged on its left hand end, but having the abutting ends of two connecting rails lodged at its right hand end and therefore requiring certain special provisions for securing the rails at such a joint. It will be understood that the majority of ties in an ordinary track will have both ends formed like the left hand end of the tie shown, in which the heavy transverse rib, 90 9, directly supports the base of the rail, A, as indicated in Fig. 3. A pair of clamp members, 10, 10, each formed at its upper end to embrace the end of the base flange. 95 of the rail, A, and each having an aperture near its lower end through which clamping bolts, 11, extend, are placed one on each side of the rib, 9, with the bolt, 11, passing through an opening, 12, in said rib. The upper surface, A¹, of the rail base flange being inclined to the horizontal at each side, and the clamp members, 10, engaging these inclined surfaces thus draw the rail base down on to the supporting surface of the rib, 9, in addition to securing it against lateral displacement thereon.

The rail securing clamp shown at the right hand end of the tie, in Figs. 1 and 2, may be substituted for that just described at any part of the rail, but is especially de- 110

signed for securing to the tie and at the same time coupling together the abutting ends of two adjacent rail sections in the track. For this reason, the clamp members, 13 and 14, occupy the whole distance between the flange portions, 8, 8, of the tie, and to accommodate them, the ribs, 3, are interrupted, their main portions terminating in a transverse rib, 15, and their extensions, 3^a, ending in a similar transverse rib, 16, as shown in Fig. 2. Between the ribs, 15 and 16, the heavy reinforcing rib, 17, extends transversely of the tie and directly under the position of the rail, A, and the base of the clamp member, 13, is cast to just fit between this rib, 17, and the rib, 16, as indicated in Fig. 4, and is secured in this position by a T-head bolt, 18, engaging a notch, 19, formed in the side of said clamp member, and extending through a boss, 20, in the web, 2, of the tie, with a nut, 21, engaging its threaded lower end. The upper portion of the clamp, 13, is formed to engage the inclined upper surface, A¹, of the rail base flange, and the clamp member, 14, is likewise formed at its upper portion. The lower part of said member, 14, however, is secured in the tie by means of a round tapered pin, 22, carried horizontally in bearing sockets at 23 and 24, in the flange portions, 8, and bearing against a groove or channel, 25, extending horizontally in the outer side of the clamp member, 14, and slightly inclined to the direction of its rail-engaging jaw, so that longitudinal movement of the tapered pin, 22, with respect to the clamp member, 14, tends to crowd said member against the rail, A, forcing the member, 13, hard against the rib or abutment, 16, which is reinforced against such pressure by the ribs, 3^a. Preferably such longitudinal movement of the tapered pin, 22, is secured by threading its smaller end at 26, and threading the socket, 24, which carries it, providing the opposite end of the pin with a hexagonal head, 27, by which it may be rotated by any suitable wrench. If desired a lock nut, 28, may be applied to the threaded end, 26, to maintain the adjustment.

To protect the tapered pin, 22, and its bearing groove, 25, against rusting, so that it may be readily released or adjusted occasionally in renewing the rails, A, or merely tightening the clamp, the wall of the bearing groove, 25, may be continued in the form of a sleeve, 29, inclosing the pin, 22, though with sufficient looseness to permit its full range of adjustment and to accommodate a quantity of protective and lubricating grease or oil for preserving the surfaces of the pin and its cooperating parts. And, if desired, a protective hood, 30, may be provided for the head, 27, of the pin, 22.

65 The clamping device at the rail joints

may also be made to serve the purpose of an anti-creep by casting a lug, 31, in the jaw of the member, 13, near each end thereof, and forming the base flange of each of the rails, A, with the notch, 32, close to the end 70 of the rail for engaging one of the lugs, 31. In accordance with well understood practice, the rails, A, if laid in moderately cool weather, should be placed with their adjacent ends spaced apart by some distance to 75 allow for longitudinal expansion of the rail upon increase of temperature, and for the same reason, the notches, 32, should be elongated to permit this relatively slight movement with respect to the lugs, 31, of the 80 clamp; but the said lugs will retain the rail ends within the clamp and check the tendency toward bodily longitudinal movement of the rails, which is nearly always present in any portion of a railway track on 85 account of the effect of traction or braking of trains running thereon.

In Fig. 4 the heavy reinforcing rib, 17, is shown as lower than the marginal flanges, B, and not extending up for direct engagement 90 with the under surface of the rail base. Instead, the clamping members, 13 and 14, are each formed with an inwardly-projecting portion, 13^a and 14^a, respectively, whose upper surface extends directly under the rail 95 base, and whose lower surface is lodged upon the rib, 17. The effect of this construction is that the clamping members, 13 and 14, act primarily to join the two abutting ends of the rail, A, A, being clamped over 100 the base flanges of said rail by the wedging action of the taper pin, 22, reacting against the rib, 16, of the tie, while the assembled joint thus formed is merely retained in the tie by means of the bolt, 18, and the concave 105 form of the groove or channel, 25, in which the taper pin, 22, acts. The joint as a whole is lodged upon the rib, 17, and thus the weight of the trains passing over the track rails, A, is transmitted to the portion, 13^a 110 and 14^a, of the clamp members and through the rib, 17, to the tie.

Fig. 6 illustrates a slight modification in which the rib, 17^a, extends directly in contact with the base of the rail, the clamp members, 115 13^a and 14^a, being formed without the portions, 13^a and 14^a, having no part in sustaining the load on the rail but acting entirely for securing the rails to the tie. In this case the top surface of the rib, 17^a, cooperates 120 with the inclined overhanging surfaces of the clamping jaws of the members, 13^a and 14^a, for alining the abutting ends of the two adjacent rail sections, A, and it may be understood that the member, 13^a, is provided 125 with lugs similar to those shown at 31, in Fig. 2 for checking undue longitudinal movement of the rail over the tie.

I claim:

1. A railroad tie of cast metal comprising 130

- vertical flanges extending transversely of the rail and an integral seating rib connecting them in position to support a rail, an abutment extending parallel to such rib and spaced therefrom, a rail-clamping member having its base lodged between the seating rib and said abutment with a jaw portion engaging the base flange of a rail, a second clamping member having a coöperating jaw engaging the rail base at the opposite side, and a round tapered member journaled in the said vertical flanges adjacent said second clamp and adjustable in the direction of its axis for crowding the clamp against the rail base.
2. In the combination defined in claim 1, means opposing the adjustment of said tapered member in direction for releasing the clamp.
3. In the combination defined in claim 1, one end of said tapered member being threaded and carried in a threaded socket in the flange of the tie, whereby its adjustment in the direction of its axis is effected by rotation in said threaded socket.
4. In the combination defined in claim 1, one end of said tapered member being threaded and carried in a threaded socket in the flange of the tie, whereby its adjustment in the direction of its axis is effected by rotation in said threaded socket, and a jam nut on said threaded portion outside the threaded socket for maintaining the parts in adjusted relation.
5. In the combination defined in claim 1, the second clamp member having a concave groove or channel in its side to receive the tapered member whose engagement with such concave groove interlocks the clamp with the tie preventing its upward withdrawal therefrom.
6. In the combination defined in claim 1, means interlocking the first clamping member with the tie preventing its withdrawal therefrom.
7. In the combination defined in claim 1, the second clamp member having a concave groove or channel in its side to receive the tapered member whose engagement with such concave groove interlocks the clamp with the tie preventing its upward withdrawal therefrom, and means interlocking the first clamping member with the tie also preventing its withdrawal therefrom.
8. In the combination defined in claim 1, the second clamp member having a concave groove or channel in its side to receive the tapered member and the wall of such groove being extended to form a tubular sheath enclosing the tapered member, with clearance for its longitudinal adjustment.
9. In combination with a railroad rail and a tie formed with a seat for the rail and with a recess at the side of such seat, a rail-fastening member comprising a lower portion lodged in said recess and a hook-shaped portion extending over the base flange of the rail, said lower portion having a groove approximately parallel to the rail, the tie having sockets at its opposite sides opening into the recess adjacent the ends of such groove, and a tapered pin in said sockets engaging the groove of the fastening member.

In testimony whereof, I have hereunto set my hand at Chicago, Illinois, this 26th day of April, 1919.

FRANK MAJKOWSKI.
